UNITED STATES PATENT OFFICE.

WORCESTER R. WARNER AND HENRY M. LUCAS, OF CLEVELAND, OHIO,
ASSIGNORS TO WARNER & SWASEY, OF SAME PLACE.

LATHE-TOOL.

SPECIFICATION forming part of Letters Patent No. 632,544, dated September 5, 1899.

Application filed March 27, 1899. Serial No. 710,608. (No model.)

To all whom it may concern:

Be it known that we, WORCESTER R. WARNER and HENRY M. LUCAS, citizens of the United States, residing at Cleveland, in the 5 county of Cuyahoga and State of Ohio, have invented a certain new and useful Improvement in Lathe-Tools, of which the following is a full, clear, and exact description, reference being had to the accompanying drawings.

10 The invention relates to a device which is adapted to serve as the means for securing a tool to a lathe-turret and for holding said tool in proper relation to the work.

15 The object of the invention is to provide a simple and efficient device of this character which will permit the user to readily change the working position of the tool relative to the axis of the work after the tool has been fixed in the holder and to withdraw the tool 20 from its working position, and thus prevent it from marking the work in running off after it has completed its cut.

25 The invention consists in the construction and combination of parts substantially as 30 hereinafter described, and definitely pointed out in the claims.

In the drawings, Figure 1 is a front elevation of the complete device. Fig. 2 is a plan view of the same, partly in section, when it is 35 attached to a lathe-turret. Fig. 3 is an end elevation of the right end of the device as shown in Fig. 1, and Fig. 4 is a detached view of the slide C and its adjusting mechanism.

Referring to the parts by letters, A represents what may be called the "base-block" 40 of the device, which is adapted to be secured to the turret and is of suitable shape for supporting the other parts of the device in proper relation to each other. The two back-rests B are mounted and movable in suitable 45 grooves in the block A, and they lie on one side of the hole a in the block through which the work passes. They are adjusted toward the axis of this hole by means of the setting screws b. On the opposite side of this hole a lies the tool-block D. This block is pivoted to the block A, the pivot, as shown, being a cylindrical stud a', secured to the block A. The block D is mounted on this stud, 50 and it is held thereon by a screw a''. This tool-block D has a suitable recess d, (indicated

by dotted lines in Fig. 1,) through which the tool H passes and in which it is held by the set-screws d' d''. The tool-block also has an arm d'', in which is a slot d'''.

55

In the top of the base-block A is a groove a'', in which a slide C is fitted, which slide is provided with upwardly-extended lug c. A plate F, which is rigidly secured by screws or other suitable means to the base-block A, lies 60 over this slide and holds it down in said groove. It is provided with an upwardly-extended lug f.

An eccentric sleeve G, having an operating handle g, passes through the slot d''', which it 65 fits, and is rotatably mounted on slide C. In the construction shown this sleeve embraces and is adapted to turn upon a stud c', which is secured to said slide. It is obvious that by taking hold of the handle g, and thereby 70 turning the eccentric sleeve, the tool-block may be caused to rock upon its pivot, so as to carry the tool into its working position, as shown in Fig. 1, or back from its working position, as desired. A suitable stop should 75 be provided to stop the movement of the block when the tool has reached its working position. It matters not whether this stop acts upon the tool-block or its arm d'' or upon the eccentric sleeve or upon the handle of 80 said sleeve. In the construction shown, however, this stop is a lug c'', projecting forward from the block D into the path of the handle g.

Means are provided for moving the slide C 85 relative to the base-block and for holding it in any desired position, which means, as shown, consists of a screw E, which has right-hand threads on that part which screws through the lug f and left-hand threads on 90 that part which screws through the lug c. This movement of the slide C moves the eccentric sleeve bodily to right or left, and thereby swings the tool-holder on its pivot, wherefore when the eccentric sleeve is turned 95 on its axis to the position shown in Fig. 1 the tool will be nearer to or farther from the axis of the work, as the case may be, than before the slide was so moved.

Any suitable means may be provided for 100 connecting the base-block to the turret. The particular construction shown is intended

to be secured to a hexagonal hollow turret by means of bolts which pass through holes in the turret and screw into threaded sockets in the base-block.

5 Having described our invention, what we claim as new, and desire to secure by Letters Patent, is—

1. The combination of a base-block, with a tool-block pivoted thereto having a slotted 10 arm, an eccentric sleeve rotatably supported by said base-block and passing through the slot in the tool-block arm, and means for turning said eccentric sleeve, substantially as specified.

15 2. The combination of a base-block, a tool-block pivoted thereto having a slotted arm, with a slide adjustably secured to said base-block, and an eccentric sleeve rotatably supported by said slide and passing through the 20 slot in the tool-block arm, and means for turning said sleeve, substantially as specified.

25 3. The combination of a base-block, adjustable back-rests, and a tool-block pivoted to said base-block having a slotted arm, a slide mounted in a groove in said base-block, an

adjustment-screw engaging with said slide and with a part rigidly connected with the base-block, a stud carried by said slide and passing through the slot in the tool-block arm, 30 an eccentric sleeve mounted on said stud in said slot, and an operating-arm secured to said eccentric sleeve, substantially as specified.

4. The combination of a base-block, a tool-block pivoted thereto having a slotted arm, 35 with a slide adjustably secured to said base-block, and an eccentric sleeve rotatably supported by said slide and passing through the slot in the tool-block arm, and means for turning said sleeve, and a stop for limiting that movement of the tool-block which carries the tool toward its working position, substantially as specified.

In testimony whereof we hereunto affix our 45 signatures in the presence of two witnesses.

W. R. WARNER.
H. M. LUCAS.
